William E. Wine ^{Inventor}

Parker Cook.

Attorney

UNITED STATES PATENT OFFICE.

WILLIAM E. WINE, OF TOLEDO, OHIO.

DOOR ARRANGEMENT FOR RAILWAY CARS.

Original application filed January 12, 1922, Serial No. 528,654. Divided and this application filed November 10, 1922. Serial No. 600,118.

To all whom it may concern:

Be it known that WILLIAM E. WINE, a citizen of the United States of America, residing at Toledo, in the county of Lucas and State of Ohio, has invented certain new and useful Improvements in Door Arrangements for Railway Cars, of which the following is specification.

My invention relates to new and useful improvements in door arrangements for railway cars and more especially to the doors and locking means of hopper cars, and the present application is a division of my previous application, filed January 12, 1922, for door arrangements for railway cars, bearing Serial No. 528,654.

The principal object of the invention is to provide a railway car having sloping sides and a sloping chute opening with a door supporting mechanism attached to the sloping side of the car and arranged to occupy a minimum space, the mechanism being so connected to the car and so associated with the door as to minimize the chance of its becoming inoperative.

Still another object of the invention is to provide a hopper door, as above described, and to provide pivotal hooks on the sides of the hopper which will fall by gravity into engagement with ledges formed on the door, the hooks being held tightly in position by dogs pivotally mounted to the rear of the hooks.

With these and other objects in view, the invention consists in certain novel arrangements and combination of parts as will be hereinafter more fully described and pointed out in the claims.

Referring now to the drawings showing a preferred embodiment of my invention,

Fig. 1 is a view in side elevation showing a fragmentary portion of a hopper, the edge of one door and a pivotal hook locking the door in its closed position,

Fig. 2 is an end view of the same,

Fig. 3 is a fragmentary sectional view taken on line 3—3 of Fig. 1.

Fig. 4 is a fragmentary diagrammatic view of a hopper, the dotted lines showing the sets of doors in their open position, and

Fig. 5 is a diagrammatic view of two hopper doors and the stiffening member extending across the same.

Referring now to the drawings more in de-

tail, a fragmentary portion 1 of a flared side of a hopper is shown, the hopper having the sloping chute 12. On the flared side of the hopper is securely riveted a housing 2 in which is mounted a pivotal hook 3, its jaw extending downwardly. In this housing is pivotally mounted the dog 4 having the lug 5 formed at the rear thereof.

As will be noticed in Figs. 4 and 5, each hopper is provided with two sets of doors which are shown in open position by the dotted lines in Fig. 4. In Fig. 5 there is shown diagrammatically a center sill 6 and it will be seen that one door 7 of the set is to one side of the center sill while the other door 8 is on the other side of the center sill. As the doors are identical, only one set will be described. These doors 7 and 8 will be hinged as at 9, while a transverse stiffening member 10 is securely riveted to the two doors 7 and 8 and extends outwardly beyond the far side of each door as at 11.

Secured by rivets or otherwise to the outer ends 11 of the stiffening member 10 are the reinforcing angle irons 13, the upper legs of which are designed to be engaged and held by the jaws of the aforesaid hooks 3, it being remembered that there is a hook for each of the doors 7 and 8.

From the foregoing it will be seen that the invention relates particularly to cars of the type having a sloping chute, such as 12, which is connected by any suitable means to the side 1, the latter being disposed in a plane oblique to the door so as to slope inwardly from the vertical downwardly to its junction with the chute 12. The door opening, which is defined by the extreme edges of the said sloping side and the sloping chute, lies in an inclined plane extending across the car and sloping from a point near the rail upwardly toward the transverse center line of the car. The door such as 7 is arranged to lie against or parallel with the plane of the door opening. The car of the type illustrated is regularly provided with two of such hoppers and openings therefor arranged side by side across the car, one at either side of the center sill construction 6. The door-stiffening member 10 extends across the car and connects the doors 7 and 8, and its ends extend outwardly beyond the sloping hopper sides 1. The door securing members, such as the hooks 3, to-

gether with the brackets 2 therefor, lie against and parallel with the hopper side, so that these hooks engage the ends of the door-stiffening member 10 at acute angles therewith. The means for holding such doors in closed positions has generally been located at the center of the car instead of at the sides of the car, and where the same have been located at the sides of the car it 10 has generally been the practice to cause the hooks to swing at right angles with the plane of the door into engagement with the ends of the door stiffener. This requires off-set brackets upon which to pivot the 15 hooks, and the use of this type of bracket has not been wholly successful because of the remoteness of the pivot point of the hook from the side sheet of the hopper, which tends to permit a looseness and some 20 separating of parts, frequently resulting either in imperfect operation or in inability to hold the doors completely closed. This is especially true where the cars are subjected to heating, such as may result from 25 a load of freshly pulled coke, or hot ashes, as the heat will warp the parts but the closer arrangement of the hook in the present construction prevents the parts being thrown materially out of line as a result of such 30 warping.

This type of car is also frequently operated over electrified zones where the third rails are used for conducting the electric current. The third rail clearances are sometimes 35 close, but by arranging the hooks to occupy the angles corresponding with the inwardly sloping side sheets of the hopper, the clearance between the hook construction and the third rail and also between the projecting ends of the door-stiffening members and the third rail is increased.

The operation of the doors is exceedingly simple. Preferably one man will stand on each side of the car; grasping the angles 45 13, which it is to be remembered are connected by a stiffening member 10, the men swing the doors upwardly against the hopper.

When these doors have reached their 50 closed position, the pivotal hooks will drop by gravity, each engaging the upper leg of one of the angles 13, thus securely holding the doors in their closed position, after which the dogs 4 will be jammed against the rear of the hooks, thereby making it 55 impossible for the door to accidentally open. To open the doors, of course, the operation is reversed. The lugs 5 on the dogs provide surfaces which may be hit with a hammer to release the dogs, after which the hooks may be forced upwardly and the doors 60 swung to their open position.

From the foregoing it will be seen that I have provided an arrangement whereby 65 two hopper doors may be moved in unison

and will always be rigidly held in their spaced relation, the means for accomplishing this function also forming ledges which are engaged by locking devices secured to the hopper in planes extending obliquely 70 to the plane of the door. The entire construction is one which is relatively cheap, easily applicable to hopper cars and extremely efficient.

Many slight changes might be made without in any way departing from the spirit and scope of the invention.

Having thus described my invention, what I claim as new and desire to secure by Letters Patent is:—

1. A railway car having a sloping side, and a sloping chute connected thereto, a door opening defined by the edges of the said side and the said chute, the same lying in an inclined plane extending across the car and sloping from a point near the rail upwardly toward the transverse center line of the car, a door hinged to the car near the top of the said opening and arranged to be swung into a closing plane parallel with the plane of the said opening, a door-securing member affixed to the door and having a portion lying in a plane normal thereto, and a door securing means affixed to the car side, the same lying in a plane parallel with the slope of the car side and at an acute angle with the plane of the securing member co-operable therewith carried by the door.

2. In a car provided with a hopper having a downwardly sloping bottom wall and a 100 side wall sloping inwardly from the vertical and forming with said bottom wall one of the corners of the discharge opening, and a pivoted door to close said opening; the combination with a member rigid with and 105 projecting from one edge of the door across the edge of said side wall; of a latch pivotally mounted on said side wall to swing in a plane parallel thereto, said latch being extended beyond the edge of said side wall 110 and adapted to cooperate with said projecting member from the door; and means also mounted on said side wall adjacent the pivotal mounting of the latch, cooperable with said latch to lock the latter in operative 115 position.

3. In a car provided with a hopper having a downwardly sloping bottom wall and a side wall sloping inwardly from the vertical and forming with said bottom wall one 120 of the corners of the discharge opening, and a pivoted door to close said opening; the combination with a member projecting from one edge of the door across the edge of said side wall, of door supporting means carried by said sloping side wall and adapted to releasably engage the said member projecting from the door, said door supporting means being inclined to the direction of the load imposed upon said door by the con- 125

tents of the car, whereby said door supporting means transmits to said sloping side wall a force opposing outward bulging of said wall.

- 5 4. In a car provided with a hopper having a downwardly sloping bottom wall and a side wall sloping inwardly from the vertical in a downward direction and forming with said bottom wall one of the corners of the 10 discharge opening of the hopper, and a swinging door for closing said opening; the combination with a member carried by and projecting from one edge of the door across the edge of said side wall, of a latch member 15 mounted on said side wall in a plane sloping inwardly from the vertical in a downward direction, said latch member being extended beyond the edge of said side wall and being adapted to cooperate with said 20 member projecting from said door to sup-

port said door against an opening movement.

- 5 5. In a car having a discharge opening and a swinging door for closing said opening, said door being adapted to swing open 25 under the influence of gravity; the combination with a door supporting member carried by the door and projecting beyond an edge thereof, of a door supporting member carried by the car body and adapted to 30 cooperate with said member projecting from said door to support said door against opening movement, one of said door supporting members being pivoted to swing in a plane forming an oblique angle with the plane of said door and sloping inwardly from the vertical in a downward direction.

35 In testimony whereof I affix my signature.

WILLIAM E. WINE.
